UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,129,589.

Specification of Letters Patent. Patented Feb. 23, 1915.

Application filed September 10, 1907. Serial No. 392,207.

To all whom it may concern:

Be it known that I, LANSING ONDERDONK, a citizen of the United States, residing at New York, in the county of New York, State of New York, have invented certain new and useful Improvements in Looper-Operating Mechanism for Sewing-Machines, of which the following is a description, reference being had to the accompanying drawing and 10 to the letters and figures of reference marked thereon.

My invention relates to new and useful improvements in looper operating mechanism for sewing machines and has for its object to provide a looper operating mechanism, wherein the looper is so mounted as to move away from the material being stitched, while in the needle loop to assist the needle in setting the stitch.

20 A further object of my invention is to provide a machine having a work supporting post and a continuously rotating shaft with a looper mechanism which shall be located in said work supporting post, and positively 25 operated from the continuously rotated shaft.

My invention consists in the parts, improvements and arrangements hereinafter described and set forth in the claims.

30 In the drawings which show by way of illustration, one embodiment of my invention: Figure 1 is a view partly in section, showing a work supporting post, the lower portion of the needle head and my improved 35 looper operating mechanism. Fig. 2 is a sectional view showing the work supporting post and looper operating mechanism, with the parts thereof in a different position. Fig. 3 is a top plan view showing the upper 40 end of the work supporting post with the throat plate removed, and showing the looper support and looper carrier. Fig. 4 is a sectional view longitudinally of the work support and bed plate on the line of the 45 lower shaft, certain parts being removed for the sake of clearness. Fig. 5 is a diagrammatic view showing the needle avoiding and the looper pulling movement in dotted lines. Fig. 6 is a detail in side and front elevation 50 of the rock lever of my looper mechanism. Fig. 7 is a detail view of the looper support. Fig. 8 is a detail view of the looper carrier,

Fig. 9 is a detail view showing a modified form of means for giving the looper its needle avoiding movement.

55

The bed plate 1 is provided with suitable bearings 2 in which is mounted a rotating shaft 3, which receives its rotation from any suitable means. Said bed plate 1 has rising from its forward end a work support 4. 60 The machine shown in part herein is preferably of the type shown in my co-pending application, Serial Number 392,204, filed of even date herewith, although it is obvious from certain aspects my invention may be 65 used in connection with other forms of sewing machines.

The overhanging arm of the machine is provided with the usual needle head 5, at its forward end, in which reciprocates a needle bar 6 carrying a needle 7. A presser bar 8 is also mounted in the needle head 5, and carries a presser foot 9 at its lower end. Said presser foot 9 normally holds the material upon the work support 10, mounted on the 75 upper end of the work supporting post 4.

70 The feeding mechanism has been omitted from the illustrated embodiment of my invention, for the sake of clearness.

75 The looper carrier 11 is provided with a thread carrying looper 12, which is seated in a socket formed in the carrier and secured thereto by a suitable screw. Said looper carrier is mounted upon a looper support 13, which as shown in Fig. 3, is provided with 80 an outwardly extending supporting stud 14 on which the looper carrier oscillates. Said looper support is preferably secured to a supporting rod 15 which is mounted in suitable bearings 16, 17 in the upper end of the 90 supporting post.

95 The looper support 13 is provided with a downwardly extending arm 18 to which is secured an extension 19. The main shaft 3 carries a crank arm 20 at its outer end, which is provided with a ball stud 21. A rock lever 22 is pivoted at 23 to a stud 24 secured to the work supporting casing. A link 25 is secured to the ball stud 21 at one end and is pivotally connected at its other end at 26 to one arm of the rock lever 22. The other arm of the rock lever 22 is pivoted at 27 to a link 28 which in turn is pivoted to a ball stud 29, mounted on an 100

arm 30 formed integral with the looper carrier 11.

The extension 19 of the looper supporting arm 18 is pivoted at 31 to a link 32, which as shown in Figs. 1, 2 and 4 is pivoted to the link 25 at a point 33, intermediate its ends.

In the modified form of my invention shown, in Fig. 9, I have shown the link 32 connected to the crank arm 20 on the main shaft 3, and in this form of my construction, the arm 19 is extended so that the throw caused by the movements of the crank arm is practically the same as that in the other form of my invention.

I have shown the extension 19 on the looper supporting arm 18 as connected thereto by a suitable screw 34, and interlocking rib connections. It is obvious that through this connection, the length of the arm 19 may be varied.

As the main shaft 3 rotates, the crank arm 20 will oscillate the rock lever 22, which will in turn oscillate the looper carrier upon the looper support. As the link 25 is moved up and down and the lower end thereof is carried around by the crank 20, the pivotal connection 20 between the link 32 and said link 25, will cause said link 32 to move endwise and vibrate the arm 19 and thus impart a vibration to the looper support. It will be noted that the axis of the looper support 15 is located at one side of the needle path and therefore, as the looper support is vibrated about its axis, the loopers may be moved from one side of the path of the needle to the other side thereof, to give the needle avoiding movement and at the same time said looper will be moved toward or from the material. It will also be noted that the axis of the looper of the looper support 15 is supported in the rear of the needle path and therefore, the looper in moving to the opposite side of the needle for the needle avoiding movement of the looper, may be moved away from the material and away from the previous stitch. If the needle loop of the previous stitch surrounds the looper at the time the looper is given its needle avoiding movement, a certain strain will be placed upon said needle loop, which will assist in drawing up the previous stitch.

In the operation of my machine, the needle rises throwing out its usual needle loop. The looper moves forward into said needle loop and the needle rises to the upper end of its stroke. As the needle reaches the upper end of its stroke the needle thread is placed under strain, which draws the previous stitch tight. At the same time that the needle is reaching the upper end of its stroke, the looper is moving laterally to avoid the needle on its descent and said lateral movement of the looper which is away

from the material and the previous stitch draws upon the needle thread which at this time surrounds the looper and assists materially the needle in drawing up the previously formed stitch. The needle descends into the looper thread loop in the usual manner to form the new stitch and the looper retracts shedding the needle loop of the previous stitch. The moving of the looper bodily away from the previous stitch to assist the needle in setting the stitch, is not claimed herein broadly, as the same forms the subject matter of my co-pending application, Serial Number 392,206, filed of even date herewith.

The bed plate 1 is provided with a thread guiding strip 35 and a thread guiding strip 36 is secured to the work supporting post. Said thread guiding strip 36 has an inwardly extending finger 37 at its upper end. The thread is led underneath the thread guiding strips 35 and 36 and passes through the work supporting post directly in rear of the loopers in their retracted position.

The loopers 12, 12, as shown in Fig. 8, are set in the carrier 11 so that their shanks are in a line substantially parallel with the body of said loopers. The right hand looper 12 in Fig. 8 is provided with an offset portion whereby said shanks may be so located. This offset portion of the outer looper 12 has an opening therethrough for the thread of the inner looper.

Having thus particularly described my invention, what I claim as new and desire to secure by Letters Patent is:—

1. The combination of a work support, a needle, a looper, a support for said looper, means for oscillating said support whereby the looper may be swung laterally to avoid the needle, and means for moving the looper into and out of the needle loop, the axis of said looper support being at right angles to the needle path and on the side of the needle passed by the looper while entering the needle loop and at a substantial distance from the path thereof whereby as the looper is oscillated laterally it is moved away from the work support to tighten the stitch.

2. The combination of a work support, a needle, a looper, a support for said looper, means for oscillating said support whereby said looper may be swung laterally to avoid the needle, and means for moving the looper into and out of the needle loop, the axis of said looper support being disposed at right angles to the path of the needle and at a substantial distance in the rear of the path of the needle, whereby as the looper is oscillated laterally, it is moved away from the work support to tighten the stitch.

3. The combination of a work support, a needle, a looper, a looper carrier, a looper support on which said carrier is pivoted, means for operating said looper carrier and

- means for oscillating said looper support, whereby the looper may be moved laterally to avoid the needle, the axis of said looper support being disposed at right angles to the path of the needle and at a substantial distance to the rear of the path of the needle, whereby as the looper is swung laterally, it is moved away from the work support to tighten the stitch.
4. The combination of a work support, of a pair of needles, a looper for each needle, a looper carrier on which said loopers are mounted, a looper support on which said carrier is pivoted, means for oscillating the looper carrier, and means for oscillating the looper support whereby the loopers may be moved laterally to avoid the needles, the axis of said looper support being located at right angles to the path of the needle and entirely at one side of the path of both of said needles, whereby as said loopers are moved laterally, they are moved away from the work support.
5. The combination with a bed plate, of a work supporting post, a looper mounted in said work supporting post, a looper carrier, a looper support on which said carrier is mounted, a rotary shaft extending into said work supporting post, and means carried by the end of said shaft for oscillating said looper carrier, said means including a link and means connected to said link for oscillating said looper support.
6. The combination with a bed plate, of a work supporting post, a looper carrier, a looper mounted in said work supporting post, a looper carrier, a looper support on which said carrier is mounted, a rotary shaft, extending into said work supporting post and means operated from the end of the shaft for oscillating said carrier, said means including a rock lever, a link connecting said lever to the operating means on the end of the shaft, and means operated by said link, for oscillating said looper support.
7. The combination of a bed plate, a work supporting post rising therefrom, a looper mounted in said work supporting post, a looper carrier, a looper support, on which said carrier is pivoted, a rotary shaft extending into said work supporting post, a crank arm thereon, a rock lever pivoted within said work supporting post, a link connecting said rock lever to said crank arm, a second link connecting said rock lever to said looper carrier, and means operated from said link between the rock lever and the crank arm for oscillating said looper support.
8. The combination with a bed plate, a work supporting post rising therefrom, a needle, a looper, a support for the looper mounted in said work supporting post, a looper carrier mounted on said looper support, means for oscillating said looper car-
- rier for moving the looper into and out of the needle loop, and means for oscillating said looper support for moving the looper laterally when in the needle loop, the axis of said looper support being at right angles to the needle path and on the side of the needle passed by the looper while entering the needle loop and at a substantial distance from the path thereof whereby as the looper is oscillated laterally when in the needle loop it is moved away from the work support so as to assist in tightening the stitch.
9. The combination with a bed plate, a work supporting post rising therefrom, a work support carried by said post, a rotary shaft extending into said work supporting post, a crank arm on the end of said rotary shaft, a link connected thereto, a looper support mounted in said work supporting post, a looper carrier mounted on said support, a looper carried by said carrier, means intermediate said link and said looper carrier for oscillating the same and means intermediate said link and said looper support for oscillating said support.
10. The combination of a bed plate, a work supporting post rising therefrom, a rotary shaft extending into said work supporting post, a crank arm on the end of said rotary shaft, a looper support mounted in said work supporting post, a looper carrier mounted on said support, a looper carried by said carrier, a rock lever mounted in said work supporting post, a link connecting said rock lever to said looper carrier, a link connecting said rock lever to said crank arm, and means for oscillating said looper support.
11. The combination with a bed plate, a work supporting post rising therefrom, a rotary shaft extending into said work supporting post, a crank arm on the end of said rotary shaft, a looper support mounted in said work supporting post, a looper carrier mounted on said support, a looper carried by said carrier, a rock lever mounted in said work supporting post, a link connecting said rock lever to said looper carrier, a link connecting said rock lever to said crank arm, an arm carried by said looper support, a link intermediate said arm and said last named link, for oscillating said support.
12. The combination with a vertical work supporting post, a looper arranged therein, and at right angles to the line of feed, a thread guiding strip extending up the side of said work supporting post, to a position directly in rear of said looper, when said looper is retracted.
13. The combination with a looper carrier, of a plurality of loopers carried thereby, the bodies of said loopers being parallel and the shanks of said loopers being set in said carrier in a line parallel with the bodies of said looper, the offset portion of

one of said loopers being provided with an opening through which the thread of the other looper passes.

14. In a sewing machine, the combination with a frame comprising a base, an over-hanging bracket-arm and a hollow work-supporting post rising from said base, of an actuating shaft disposed transversely of said post, an oscillatory looper within said 10 post and having its blade disposed transversely of the axis of oscillation, a looper-supporting bar arranged in the upper part of said post and upon which said looper is mounted to oscillate, means connected with 15 said shaft for imparting oscillatory loop-

seizing and shedding movements to the looper, and means also connected with said shaft for tilting the looper-supporting bar through a range of movement with extreme positions within a quadrant limited at one 20 side by a line parallel with the needle-path, whereby the looper blade is given sidewise and substantial rising and falling movements.

In testimony whereof I affix my signature, 25 in presence of two witnesses.

LANSING ONDERDONK.
